UNITED STATES PATENT OFFICE.

DANIEL A. LOESER, OF SAG HARBOR, NEW YORK.

DESIGN FOR A SILVERSMITH'S STOCK.

SPECIFICATION forming part of Design No. 25,021, dated December 31, 1895.

Application filed November 30, 1895. Serial No. 570,704. Term of patent 7 years.

To all whom it may concern:

Be it known that I, DANIEL A. LOESER, a subject of the Emperor of Germany, residing at Sag Harbor, in the county of Suffolk and State of New York, have invented and produced a new and original Design for a Silversmith's Stock, of which the following is a specification, reference being had to the accompanying drawing, which shows a plan or face view thereof having my design applied thereto.

The leading or characteristic feature of my design consists of a shell-like center having on either side thereof a series of scrolls.

Referring to the drawing, A represents a shell-like center, below which is the foliated pendant B, and to either side of which are arranged several scrolls C C, and beyond which and forming the outer end of the stock are shell-like scrolls D D, the whole arranged substantially as shown.

What I claim is—

The design for a silversmith's stock as herein shown and described.

DANIEL A. LOESER.
